UNITED STATES PATENT OFFICE.

IRVIN F. WALTER AND LEWIS BENDER, OF ALLENTOWN, PENNSYLVANIA.

STAMP-CANCELER.

SPECIFICATION forming part of Letters Patent No. 308,814, dated December 2, 1884.

Application filed February 27, 1884. (Model.)

To all whom it may concern:

Be it known that we, IRVIN F. WALTER and LEWIS BENDER, citizens of the United States, residing in Allentown, Lehigh county, Pennsylvania, have invented certain Improvements in Stamp-Cancelers, of which the following is a specification.

Our invention relates to that class of stamp-cancelers in which a block or plate having an abrading-surface is guided in the head of the device and acted upon by a cam on the yielding handle, the object of our invention being to so construct a canceler of this class as to apply the force as directly as possible to the abrading-block, and thus insure the positive movement of the same necessary for the proper cancellation of the stamp.

In the accompanying drawings, Figure 1 is a longitudinal section of a stamp-canceler constructed in accordance with our invention; Fig. 2, an elevation of same, partly in section; Fig. 3, a sectional plan view on the line 1 2, Fig. 1; Fig. 4, a transverse section of the lower portion of Fig. 1 on the line 3 4, and Figs. 5 and 6 inverted plan views of the device with the abrading-block in different positions.

The canceler has a hollow head, *c*, secured to and projecting upward from which is the shank *b*, and guided on the upper end of the latter is the knob or handle *a*, connected to the upper end of the central stem, *a'*, the lower end of which is guided in an opening in the head *c*, and is secured to a block, *e*, contained within the hollow head. This block *e* has a beveled face, which bears against the correspondingly-beveled upper face of a block, *f*, guided on a bolt, *g*, which extends across the hollow head, and has a threaded end adapted to a similarly-threaded opening in one side of said head, so that it can be readily removed when it is desired to detach the parts of the canceler for any purpose. When the knob of the canceler is grasped in the hand and the head pressed down upon the face of an envel-

ope, the knob will yield and the block *e* will be depressed by the stem *a'*, so that its beveled face, acting on the beveled face of the block *f*, will cause the latter to move longitudinally from the position shown in Fig. 6 to that shown in Fig. 5; and as the lower face of the block *f* is provided with projecting sharp-pointed spurs or teeth, the latter will cut or abrade the surface of the stamp, (which will be beneath the block,) so as to insure the perfect cancellation of the same and render its further use impossible. The spring *h*, contained within the hollow head *c*, acts upon the block *f* to effect the restoration of the same to its original position, when, on removing the pressure from the knob *a*, the latter is elevated by the action of the spiral spring *k*, surrounding the stem *a'*. Considerable force is necessary in order to move the block *f* and cause its toothed face to cut through the stamp; hence we apply the power to said block as directly as possible by connecting the cam-block *e* to the lower end of the stem *a'*, the force being applied directly to the upper end of said stem.

Without claiming, broadly, therefore, a stamp-canceler in which an abrading-block is caused to move laterally across the face of the stamp by the action of a beveled cam, we claim as our invention and desire to secure by Letters Patent—

The combination of the hollow head *c* and its shank *b*, the transverse bolt *g*, the block *f*, guided thereon, having a toothed lower face and a beveled top, the springs *h* and *k*, the knob *a*, having a stem, *a'*, and a beveled block, *e*, secured to the lower end of said stem and acting upon the beveled top of the block *f*, as set forth.

IRVIN F. WALTER.
LEWIS BENDER.
